UNITED STATES PATENT OFFICE.

GEORGE B. CHAPMAN, OF CHICAGO, ILLINOIS, ASSIGNOR OF ONE-FOURTH TO
DAVID Q. STEPHENS, OF SAME PLACE.

TOY OR PUZZLE.

SPECIFICATION forming part of Letters Patent No. 665,671, dated January 8, 1901.

Application filed September 15, 1900. Serial No. 30,165. (No model.)

To all whom it may concern:

Be it known that I, GEORGE B. CHAPMAN, a citizen of the United States of America, and a resident of Chicago, county of Cook, and State of Illinois, have invented certain new and useful Improvements in Toys or Puzzles, of which the following is a specification.

This invention relates to that class of toys or puzzles in which a rolling globe is adapted to roll freely within an inclosed field and by the manipulation of the containing-field is intended to reach a desired goal difficult of attainment, and thus afford entertainment to the operator.

The object of the present invention is to provide a simple, cheap, and durable toy or puzzle in which the attainment of the goal is rendered very difficult, yet possible, all as will hereinafter more fully appear, and be more particularly pointed out in the claim. I attain such object by the construction and arrangement of parts illustrated in the accompanying drawings, in which—

Figure 1 is a perspective view of a toy or puzzle constructed in accordance with the present invention; Fig. 2, a central sectional elevation of the same; Fig. 3, an enlarged detail elevation of the ball or globe; Fig. 4, a similar sectional elevation of the same at line xx , Fig. 3.

Similar numerals of reference indicate like parts in the several views.

Referring to the drawings, 1 represents the flat field or base, inclosed by a marginal wall or fence 2, preferably circular in form, as shown, but which may be of any other required form, as the judgment of the maker may suggest.

3 is the goal, which in the present improve-

ment is in the form of a vertical plate having 40 a central goal-recess 4 and inclined tracks 5, leading from the surface of the field 1 to said goal-recess 4, as shown. Such goal 3 is preferably arranged in the center of the field 1, but may be arranged in any other part of such 45 field without departing from the spirit of this part of the present invention.

6 is the rolling globe or ball of the present invention, formed with a central circumferential recess 7, dividing the globe-ball into two 50 semispheres, which are united together by a centrally-arranged stem 8, as illustrated in Figs. 3 and 4.

In use, the operator, holding the field 1 in his hand, will manipulate the same so as to 55 cause the globe or ball 6 to roll upon the field, with the object in view of having the central annular recess 7 of said globe straddle an inclined track 5 and roll into the goal 4.

Having thus fully described my said invention, what I claim as new, and desire to secure by Letters Patent, is—

A toy or puzzle comprising a field having a surrounding fence, a goal formed by a raised track having a central goal-depression and 65 inclined ends leading to such depression, and a rolling globe having a circumferential recess adapted to straddle said track and guide the ball in its movement upon the track toward the goal-depression, substantially as 70 set forth.

Signed at Chicago, Illinois, this 12th day of September, 1900.

GEORGE B. CHAPMAN.
